[57] CLAIM

The ornamental design for a garden tool sleeve, as shown and described.

DESCRIPTION

FIG. 1 is a perspective view of a garden tool sleeve showing our new design, the broken-line disclosure of a tool handle being for illustrative purposes only and forming no part of the claimed design;

FIG. 2 is an enlarged front elevational view thereof;

FIG. 3 is an enlarged rear elevational view thereof;

FIG. 4 is an enlarged top plan view thereof;

FIG. 5 is an enlarged bottom plan view thereof;

FIG. 6 is an enlarged right side elevational view thereof; and,

FIG. 7 is an enlarged left side elevational view thereof.
